UNITED STATES PATENT OFFICE.

GENTRY F. LIVESAY, OF ST. LOUIS, MISSOURI, ASSIGNOR OF ONE-THIRD TO
JAMES S. LIVESAY, AND ONE-THIRD TO RUSSELL D. BUSH, OF CERESCO,
NEBRASKA.

CURTAIN-FIXTURE.

No. 857,743.

Specification of Letters Patent.

Patented June 25, 1907.

Application filed February 3, 1905. Serial No. 243,997.

To all whom it may concern:

Be it known that I, GENTRY F. LIVESAY, a citizen of the United States, residing at St. Louis, State of Missouri, have invented a new and useful Improvement in Curtain-Fixtures, of which the following is a specification.

This invention is an improved construction of curtain fixture, the object being to provide means whereby a curtain as a whole can be adjusted vertically with reference to the window frame so that light can be permitted to enter the room, either above or below or both above and below, the curtain, said curtain being arranged to be rolled and unrolled independent of the vertical movement of the curtain as a whole.

With these objects in view, the invention consists in the novel features of construction, combination and arrangement, all of which will be fully described hereinafter and pointed out in the claims.

In the drawings forming a part of the specification:—Figure 1 is a face view of a window provided with a curtain hung by means of my improved construction of fixture. Fig. 2 is an end view of the curtain roller and the movable bracket in which said end is journaled. Fig. 3 is a vertical sectional view of the same. Fig. 4 is a sectional view on the line 4—4 of Fig. 3, looking in the direction of the arrow. Fig. 5 is a detail perspective view of the elevating cord guide. Fig. 6 is a sectional view of the same.

Referring to the drawing, A indicates the window and B, the window frame, which are of the usual or any approved construction. Guide blocks C, of metal porcelain or any other suitable material, are secured to the top of the window frame adjacent the opposite ends and passing through said guides are the elevating cords D, which have brackets E, connected to their lower ends and journaled in said brackets are the ends of the roller F, carrying the curtain G. The roller F, is reduced at the opposite ends as shown at F' and connected to said reduced portions and wound about the same are the cords H, which serve to wind the curtain G upon the roller F, when the said cords are pulled down.

When the curtain is pulled down, these cords are wound upon the reduced ends of the pole, weights I, being carried upon the lower ends of said cords for the purpose of keeping them always taut. A ring or other suitable form of handle K, is attached to the bottom strip of the curtain and by means of which it can be unrolled from the roller when it is desired to unroll the curtain. The extreme end of the roller is formed into a pintle F² which passes through an opening E² in the bracket E and is secured in place by means of a screw E'.

In operation the curtain as a whole is raised or lowered by manipulating the raising and lowering cords H, which are normally fastened to a cleat L attached to the side of the window. After the curtain has been raised or lowered as a whole to the desired point, the curtain proper can be rolled or unrolled by pulling upon the cords H or upon the handle K or the cords H.

It will thus be seen that I provide an exceedingly cheap, simple and easily operated construction of fixture by means of which the curtain as a whole can be adjusted to permit light to enter either above or below, or both above and below the curtain.

Having thus fully described my invention, what I claim as new and desire to secure by Letters Patent, is:—

1. A curtain fixture comprising a roller having a curtain connected thereto, the ends of said roller being reduced and provided with pintles mounted in disk shaped brackets provided with perforated lugs, the pintles being secured therein by screws, cap shaped guide blocks secured to the frame, provided with oppositely arranged openings, cords passing through said blocks, connected to the perforated lugs of the brackets, and cords connected to the reduced ends of the roller adapted to work between the shoulder of the roller and the bracket, and provided with weights at their free ends, as set forth.

2. A curtain fixture comprising a roller having a curtain connected thereto, the ends of said roller being reduced, the cords connected to and wound upon the reduced por-

tions and having weights at their lower ends, the extreme ends of the roller being provided with pintles, the disk shaped brackets in which the pintles are journaled together with 5 means for fastening the pintles in said brackets, the elevating cords connected to said brackets and the cap shaped guide blocks at-

tached to the window frame provided with openings and through which the elevating cords pass, substantially as described.

GENTRY F. LIVESAY.
